UNITED STATES PATENT OFFICE.

JERRY U. FORBES, OF CINCINNATI, OHIO.

COLLAPSIBLE SHAFT.

Application filed November 15, 1924. Serial No. 750,148.

To all whom it may concern:

Be it known that I, JERRY U. FORBES, a citizen of the United States, residing at Cincinnati, in the county of Hamilton and State 5 of Ohio, have invented certain new and useful Improvements in Collapsible Shafts, of which the following is a specification.

My invention relates to winder shafts for supporting and winding or unwinding paper 10 or other sheet material, and its object is to provide a device of this character which is conveniently removed from or inserted into a roll of such material, of simple, light, compact construction and having ample strength 15 and durability. A further object is to make such a device suitable for use where the material is wound by the application of the power through the shaft, or for use where the rotation is imparted through means contacting with the periphery or outer convolution 20 of the roll; in the latter case providing for secure fastening of the device in expanded condition by simple and easily operated means whereby the device so fastened may 25 be quickly released and collapsed for removal from the roll. Other objects will appear in the course of the ensuing description.

I attain these objects by the device illustrated, for example, in the accompanying drawing, in which—

Figure 1 is a plan view, the device being expanded;

Fig. 2 is an enlarged sectional plan view 35 of the same, the section being on the plane of the line 2—2 of Fig. 3;

Fig. 3 is a cross-section of the same, expanded;

Fig. 4 is a similar section, the device being contracted or collapsed; and

Fig. 5 is an end view of the device, expanded, with the initial turns of material therearound, illustrating the manner of starting a winding thereon.

As I prefer to construct my invention, there is a shaft 1 having a keyway extending longitudinally between two inversely positioned collars 2 and 3 near respective ends of the shaft, in which keyway is a key 4 extending from one collar to the other. The portions of the shaft 1 between the collars and the respective ends of the shaft form the journals which will be understood to bear in suitable bearings, not shown, in the machine wherein the device is used, as a paper-making machine, which bearings can

be opened to allow the shaft to be put in or taken out of them. At suitable intervals between the collars 2 and 3, cam members 5 are secured on the shaft 1 by the key 4. 60 In this example there are six such cam elements 5 in each of two groups separated by a considerably longer interval midway of the length between the collars 2 and 3; the sectional view in Fig. 2 showing one of these 65 groups and it being understood that the other half of the length of the device, omitted in Fig. 2, is of the same construction as regards these cam members 5.

Each cam member 5 has its periphery 70 formed with three cam surfaces all equally eccentric to the shaft 1 and diverging therefrom in the same circumferential direction; each two adjacent cam surfaces 6 being separated by a stop member 7, and the peripheral surfaces of these stop members 7 all being concentric with the shaft and of equal radii so as to fit snugly inside the sleeve 8 which has fitting snugly but rotatably in its opposite ends the reduced journal parts 80 9 of the respective collars 2 and 3 and the ends of the sleeve 8 fitting snugly against the shoulders resulting from these reduced parts, so that the collars 2 and 3, being clamped to the shaft 1 by the set screws 10, 85 prevent appreciable end play of the sleeve 8 relatively to the shaft 1. The exterior of the sleeve 8 and the exteriors of the collars 2 and 3 are of the same diameter, so that their surfaces are practically continuous. 90 The cam members 5, keyed tightly to the shaft 1, are rotatable in the sleeve 8 as are the reduced parts of the collars. Thus, the shaft 1, members 5 and collars 2 and 3 can turn unitarily in the sleeve 8. 95 The collar 2 at one end, however, as shown in Figs. 2 and 5, has the screw pin 11 tapped into it parallel with the shaft axis and centering in the circle of contact of the sleeve 8 with the reduced part of the collar 2, which 100 parts have recesses 12 and 13 which may register; the recess 12 of the collar 2 being a continuation of the opening into which the screw pin 11 is tapped. This pin 11 has a reduced unthreaded end part or bit 105 14, which when the screw pin is turned to one position occupies the recess 12 only, but when the pin is turned 180 degrees this bit 14 occupies the recess 13 of the sleeve 8, thereby locking the sleeve 8 and collar 2 together. Preferably, this bit and the recesses 110 are correspondingly tapered, so that, the

screw pin being screwed in slightly in the half turn, the bit 14 wedges in the recess 13 in the locking operation. In its opposite position, with the bit 14 only in the collar recess 12, the shaft and attached parts can be turned in the sleeve as before described.

The sleeve 8 has, at equal intervals there-around, the two groups of longitudinal slots 15, there being three slots in each group. These groups correspond with the two groups of cam members 5 and the slots terminate close to the respective inner ends of the groups of members 5, leaving the middle portion of the sleeve 8 unslotted. Oppositely, the slots 15 extend almost to the respective collars 2 and 3. Each one of the three gripping bars 16 is of T-shaped cross-section throughout its length except in its middle part; the stem part of the T-shape extending out through a respective slot 15, thus forming the exterior bearing element of the bar. The transverse parts of the shape lie against corresponding cam surfaces 6 of the members 5, forming the inner bearing element of the bar as well as acting as a stop to prevent escape of the bar through the sleeve slot 15. These bars 16 thus ride on the cam surfaces 6; being pushed out radially when the cam members 5 and sleeve 8 are rotated relatively to each other in one direction, and being allowed to collapse radially inwardly when these parts are rotated relatively to each other in the opposite direction. Preferably these cam members 5 and bars 16 are so proportioned that in the expanded position the inner bearing members of the bars engage against the interior of the sleeve 8 along the edges of the slots 15, and when collapsed the outer edges of the outer bearing members of these bars 16 lie even with the exterior surface of the sleeve 8, so that, in collapsed condition, the device has a practically continuous cylindrical surface from one journal part to the other, as indicated in Fig. 4.

The screw-pin receiving recess 13 is so located in the sleeve 8, with relation to the positioning of the cam members 5 and the collar 2 with its screw pin 11 on the shaft 1, that the screw pin bit 14 can enter the recess 13 when the bars 16 have been forced by the cam members 5 to their most extended positions, which is when these bars engage with and are stopped by the respective stop members 7 of the cam members 5; so that the screw pin 11 locks the device in expanded condition. The opposite sides of the stop members 7 act as stops for the bars 16 at the limit of contraction, as seen in Fig. 4. Fig. 2 illustrates the expanded condition; but the screw pin is shown in unlocking position. When the device is used for winding with the motion imparted through the shaft 1, it is not necessary to lock the device with this pin 11; and it will be understood that if the

device is constructed for that purpose only, this locking provision may be omitted, because if the material A (Fig. 5) is wound on in the direction indicated, the driving force keeps the cam members 5 pushed tightly against the bars 16, which in turn bear tightly against the edges of the slots 15, preventing the bars 16 from traveling to the radially inward parts of the cam surfaces 6 for collapse.

However, where the winding is effected by allowing the roll to rest on driving rollers, and the shaft 1 merely has bearings to steady the roll while thus driven, there is no substantial tendency to hold the bars 16 outward. Therefore, to avoid the gradual slip-page of these bars inward down the cam surfaces 6 in the jarring incident to driving, which would result in the steadyng shaft becoming ungripped from the interior of the roll, I provide the locking screw pin 11 as described.

When the roll is completed the shaft 1 is released from its bearings in a manner well known in the art as before mentioned herein, and, if the screw pin 11 has been used to lock the device, it is given a half turn by a suitable wrench applied to its hollow outer end part, releasing the shaft to be turned relatively to its sleeve 8, causing the bars 16 to ride down away from the gripped roll, permitting the entire device to be withdrawn from the roll. For starting the winding, the shaft 1 is turned in the sleeve 8 to force the bars 16 up the cam surfaces 6, whereupon it may be locked by a half turn of the screw pin 11. Then the shaft is put into its bearings, and the paper or other material is manually held to one of the bars 16 until a succeeding convolution of the material wraps tightly over it, clamping it for initial winding as seen in Fig. 5. As the winding progresses the grip of the material around the projected bars 16 will be further tightened. The device of course also is suitable for receiving a completed roll for unwinding; it being inserted into the roll and then expanded so that the bars 16 grip the interior of the roll. Thus, my invention, constructed on a larger or smaller scale as the case may be, is suitable for use not only in paper making machines and other devices where sheet material, rolled, woven or otherwise manufactured, is wound up in course of manufacture; but may be used where rewinding is done, as in paper manufacture and the like, or where the material is unwound for use, as in printing machines, registers using long webs or tapes, and other similar devices.

By having the gripping elements 16 of considerable length, the material is gripped substantially uniformly; and by having these elements relatively narrow, the gripping pressure is concentrated and intensified

notwithstanding the considerable length. By providing a plurality of cam elements at intervals of the lengths of the gripping elements 16, the latter are supported firmly 5 against the material, although these elements 16 are relatively light in cross-section. Being of T shape, with their wide parts against the cam elements, they have their greatest bearing area where it is the 10 more needed; against the hard metallic cam surface where repeated friction occurs, rather than against the softer material A, where the friction is largely static with much less wearing action. Also, this dis- 15 position of the T shaped gripping elements 16 results in stoppage of these elements from escape through the slots 15, and, the outer gripping parts being only of the width of the slots, they can be withdrawn flush with 20 the surface, so that the device has a practically unbroken peripheral surface when it is to be withdrawn from or inserted into a roll of material, avoiding any difficulty if the interior of the roll happens to be 25 abraded, torn and rough, or the inner layers of the roll wrinkled so as partially to clog the interior passage that is to receive the collapsible shaft. By discontinuing the slots 15 at the middle of the device, undue 30 weakening of the sleeve 8 is avoided; yet the resultant discontinuation of the ribs of the gripping members 16, weakening these at their middles, is not objectionable, owing to the ample support of these members 16 35 by the cam members 5, arranged in the separate groups against the active portions of the gripping members 16.

The foregoing details of construction are preferred, for the reasons stated. However, 40 modifications may occur as to these details, as well as in the number of members 16 and corresponding cam parts, or the number of cam members, or in other respects, depending upon conditions of use.

45 Therefore, I do not wish to be understood as being limited to the precise disclosure herein, but having thus fully described my invention, what I claim as new and desire to secure by Letters Patent is:

50 1. In combination, a shaft, a cam member fixed on said shaft, having its periphery made up of alternating eccentric surfaces and substantially concentric surfaces projected beyond the eccentric surfaces, a 55 sleeve rotatably fitting around said projected surfaces, having longitudinal slots opposite the respective eccentric surfaces, and bars bearing on the respective eccentric surfaces and projecting through the respective slots.

60 2. In combination, a shaft, a cam member fixed on said shaft, having its periphery made up of alternating eccentric surfaces and substantially concentric surfaces projected beyond the eccentric surfaces, a

sleeve rotatably fitting around said projected surfaces, having longitudinal slots opposite the respective eccentric surfaces, and bars, each of T-shaped cross-section, having its transverse members bearing on 70 a respective eccentric surface and having the stem member of its cross-section projecting through the respective slot.

3. In combination, a shaft, collars fixed on said shaft, a cam member fixed on said shaft between said collars, having its periphery made up of alternating eccentric surfaces and substantially concentric surfaces projected beyond the eccentric surfaces, a sleeve rotatably fitting around said projected surfaces and having its ends rotatably fitting on the respective collars, said sleeve having longitudinal slots opposite the respective eccentric surfaces, and bars bearing on the respective eccentric surfaces and 80 projecting through the respective slots.

4. In combination, a shaft, collars fixed on said shaft, a cam member fixed on said shaft between said collars, having its periphery made up of alternating eccentric surfaces and substantially concentric surfaces projected beyond the eccentric surfaces, a sleeve rotatably fitting around said projected surfaces and having its ends rotatably fitting on the respective collars, said sleeve having longitudinal slots opposite the respective eccentric surfaces, locking means on 90 one of said collars, adapted to be engaged with or disengaged from said sleeve, and bars bearing on the respective eccentric surfaces and projecting through the respective slots.

5. In combination, a shaft, collars fixed on said shaft, a cam member fixed on said shaft between said collars, having its periphery made up of alternating eccentric surfaces and substantially concentric surfaces projected beyond the eccentric surfaces, a sleeve rotatably fitting around said projected surfaces and having its ends rotatably fitting on the respective collars, said sleeve having longitudinal slots opposite the respective eccentric surfaces, locking means rotatably mounted in one of said collars and having 105 a projection adapted to be engaged with or disengaged from said sleeve by rotation of said locking means, and bars bearing on the respective eccentric surfaces and projecting through the respective slots.

6. In combination, a shaft, collars fixed on said shaft, a cam member fixed on said shaft between said collars, having its periphery made up of alternating eccentric surfaces and substantially concentric surfaces projected beyond the eccentric surfaces, a sleeve rotatably fitting around said projected surfaces and having its ends rotatably fitting on the respective collars, said sleeve having longitudinal slots opposite the 115 respective eccentric surfaces, one of said col-

lars and the adjacent part of the sleeve having recesses adapted to register, locking means rotatably mounted in said one of said collars on an axis substantially parallel with said shaft, having a projection engageable within the sleeve recess or removable therefrom entirely into the collar recess upon rotation of said locking means, and bars bearing on the respective eccentric surfaces and projecting through the respective slots.

7. A collapsible shaft comprising a tubular member directly receiving material to be wound thereon and having a longitudinal

slot, a gripping member projecting through said slot and extending along said slot, and a cam member having a periphery comprising an eccentric surface and a substantially concentric surface projected beyond the eccentric surface and forming a bearing against the interior of the tubular member for rotation of the cam member in the tubular member, said gripping member bearing against and being operatively supported by the eccentric surface of said cam member.

JERRY U. FORBES.
